CLAIM

The ornamental design for an inflatable towable vehicle, as shown and described.

DESCRIPTION

FIG. 1 is a perspective view showing my new design;

FIG. 2 is a top plan view thereof;

FIG. 3 is a rear elevation view thereof;

FIG. 4 is a right side elevation view thereof;

FIG. 5 is a front elevation view thereof;

FIG. 6 is a left side elevation view thereof; and,

FIG. 7 is a bottom plan view thereof.

The broken lines showing stitching on the inflatable towable vehicle, straps, and tow line sections of FIGS. 1-7 form no part of the claimed design.
